UNITED STATES PATENT OFFICE.

KARL WIEDEN, OF OHLIGS, GERMANY.

TINDER-BOX.

1,257,567.

Specification of Letters Patent. Patented Feb. 26, 1918.

Application filed July 9, 1917. Serial No. 179,525.

To all whom it may concern:

Be it known that I, KARL WIEDEN, manufacturer, subject of the King of Prussia, German Emperor, residing at Ohligs, in the 5 Province of the Rhine, Germany, have invented certain new and useful Improvements in Tinder-Boxes, of which the following is a specification, reference being had therein to the accompanying drawing.

10 My invention relates to improvements in and relating to tinder-boxes of that kind, in which a liquid fuel, such as benzene or the like, contained in a suitable fountain or reservoir, feeds a wick and is ignited by sparks

15 produced by rubbing a pyrophorous metal of a known kind against a rough or milled circumference of steel or the like. The object of my invention is to obtain a considerable economy of the fuel in tinder-boxes

20 and pocket-lamps of the said known kind, the said improvements being equally adapted to continue the feeding of the liquid fuel to the wick for any suitable length of time, thus enabling the tinder-box to be employed

25 as a lamp.

I obtain the purposes set forth by providing means for stopping the liquid fuel from being fed to the wick from the fountain or reservoir when the tinder-box or lamp is out 30 of use. Such means may be of various kinds and they may be employed in a variety of manner, of which I am going to describe some specimens in the following specification.

35 In lamps it is known to feed the liquid fuel from the fountain or reservoir to the wick or match of the burner by a separate wick. If I would employ such means I would make the tinder-box inoperative, be- 40 cause a surplus of fuel would be fed to the burning wick, thereby producing an excessive flame.

My invention, therefore, consists, accord- 45 ing to one modification, in constructing the tinder-box in such a manner, that the fountain or reservoir containing the liquid fuel may be reversed so that, in one position, the wick-end destined to burn projects to the outside of the fuel-box, while in the opposite 50 position said wick-end immerses into the liquid fuel. When out of use, i. e., for the greater part of time, the box takes the for- 55 mer position and no fuel is conveyed by suc- tion from the fountain. If, then, the burner is turned into the opposite position, the wick contains enough of the fuel for producing a

flame for a short time. The burner, then, is again reversed into the state of rest. But for using the burner as a lamp, the position is maintained, in which the lower or idle 60 wick-end immerses into the fuel and raises enough of it to produce a lighting flame.

It will be readily understood, that a variety of forms of construction may be ex- 65 ecuted for carrying the invention into prac- tice. To make my invention perfectly understood, I have illustrated some forms in the accompanying drawings, in which:

Figure 1 shows my improved device in the state of repose and

70 Fig. 2 the same in the state of use, both in vertical section.

Fig. 3 represents the invention in the form of a pocket-lamp in the state ready for use, and

75 Fig. 4 the same in the state of repose.

In Fig. 5 another modification is illus- trated in position of use, and in

Fig. 6 in the state of rest.

Fig. 7 represents a further construction 80 in the position of repose;

Fig. 8 shows the same in the position of use, and

Fig. 9 is a section on line A—B of Fig. 7.

Finally, Figs. 10, 11 and 12 represent a 85 still further construction of my invention in positions similar to those shown in Figs. 7, 8 and 9.

Referring to Figs. 1 and 2, *a* designates the fountain containing the liquid fuel; 90 within the lower end of said fountain *I*, preferably, arrange a sieve or perforated bot- tom *g* and a wick *b* is guided through said fountain and its stopper and sieve, which wick may be surrounded by a metal tube, 95 leaving the upper and lower end of the wick unprotected. The said wick *b* projects into an intermediate chamber *c* of the burner, said chamber containing wad or any fibrous ma- terial ready for sucking the liquid fuel; 100 from said wadding rises the burning-wick *d*, to which sufficient fuel is communicated by the imbibed wad. The means of ignition by a pyrophorous metal are not shown in Figs. 1 and 2, forming no part of this in- 105 vention.

At or about the middle of the tubular burner two studs *f* project opposite to each other, which studs are cushioned within re- cesses of a suitable casing or stand of any 110 suitable form which may be placed on a ta- ble. The said studs may be provided with

suitable recesses which may repose on corresponding projections of the cushions to prevent turning of the burner when lodged in one of the two opposite positions shown in 5 the drawings.

When the burner takes the position of repose, as shown in Fig. 1, the inner end of wick *b* projects from the liquid fuel contained within the fountain at the bottom- 10 end of same, the said fuel, then, being at the top or stopper end of the fountain turned topside down, and no fuel is conveyed by suction from said fountain. The sieve or 15 perforated bottom *g* serves to prevent any fuel from being thrown on the projecting end of the wick if the burner becomes shaken or moved.

If the burner is to be used, the same is turned up into the position shown in Fig. 20 2; the fuel, then, will flow down to the bottom of the fountain *a* and the wick will be immersed and raise sufficient fuel to feed the burner-wick *d*. The flame is ignited by 25 striking the pyrophorous metal, not shown, and the projecting end of wick *d* will be lighted, containing a sufficient quantity of fuel from the moistened wad *c*. After using 30 the flame, the burner is returned into the position of rest shown in Fig. 1, to prevent any superfluous fuel from being removed from the fountain. But on retaining the 35 position of use shown in Fig. 2, the flame will continue to burn as a flame, which is continually fed from the fountain by the sucking wick *b*.

It will be readily understood, that a similar construction of a reversible burner containing a fuel fountain may be employed to form a lamp which may be suspended to a 40 wall or which may be carried in the pocket. It will only be necessary to provide suitable means for changing the two opposite positions of the burner and fountain and for keeping the sucking wick *b* out of reach of 45 the liquid fuel during the position of rest. In all other respects the form of the tinderbox may vary, it may be round, flat or take any suitable shape; also the mode of ignition 50 may vary, it may be performed by a revolving wheel, or by a striking or rubbing construction of any known kind.

Of course, a considerable economy of fuel 55 will be obtained by all such constructions, as no evaporation can occur during the state of repose and no vapors can escape.

In the described construction I have employed a wick *b* to convey the fluid fuel from the fountain to the intermediate space containing the wad *c*, said wick dipping 60 into the fluid only during the use of the burner. Said wick, however, may be dispensed with and replaced by a very small tubular channel, particularly in such cases, where the two chambers containing the 65 liquid fuel and the wad are not arranged one

over another but are juxtaposed. The said small communicating channel, in such cases, must be located within the partition between the two chambers at such height to prevent the fluid to enter it during the state 70 of repose. When the tinder-box is to be used, the position will be reversed and the fluid fuel allowed to escape through said channel into the space containing the wad.

This modification has been illustrated by 75 Figs. 3 and 4, showing a longitudinal section of the tinder-box.

The two spaces *a* and *c* are juxtaposed and a small channel *b* between them is provided, said channel taking the lowest position during the state of use, as shown in Fig. 3, to allow the fuel to pass from the fountain *a* to the wad *c* through said channel *b*. On reversing the position, as shown in Fig. 4, the said channel will be placed above the 85 level of the fuel, thereby rendering impossible any over-flow of fuel from the space *a* to the wad *c*. A sieve *g* placed around said channel, will, in this case too, prevent any escape of fuel through said channel by shaking the tinder-box. 90

It will be readily seen, that the result of this modified construction will be exactly the same as that described before with reference to Figs. 1 and 2; a great economy of fuel 95 will be obtained by preventing the fuel from evaporation during the state of repose, and, nevertheless, the tinder-box may be used as a lamp, by simply reversing its position.

Instead of leaving the channel *b* open, a 100 wick or porous material might be placed within said channel for preventing any ready escape of the fuel; or said wick or pad might be placed before the opening of the channel. 105

A further modification of my invention is illustrated by Figs. 5 and 6. This construction serves to facilitate the use of the tinderbox as a lamp, by providing means for a more ready conveyance of the fuel from the 110 fountain *a* to the wad *c*, corresponding to the continued consumption of fuel.

Said means consist in providing two channels, *b* and *f*, in the partition between the two chambers *a* and *c*, the one channel *b*, 115 serving to let fuel pass from the fountain *a* to the wad during the state of use, and the other channel to feed air into the fountain for facilitating the discharge of fuel. The former channel *b*, is placed below the level 120 of the fuel during the state of use and the other channel *f*, above the said level, as shown in Fig. 5, while, on turning the box for a quarter of a full turn, see Fig. 6, the channel *b*, is placed out of reach of the 125 liquid fuel and cannot pass. Fig. 5 indicates the state of use and Fig. 6 the state of repose.

In Figs. 7, 8 and 9 I have shown another modification of my invention, which con- 130

sists in obtaining the same effect, as described before, viz. economy of fuel, without reversing the position of the burner or of the whole box. This modification is a further development of that shown in Figs. 5 and 6; it consists in adding a slide-valve *i*, to the mouth of the channel *b*, opening into the wad-chamber. The said slide-valve *i*, preferably, is constructed and arranged to automatically be opened when the cover *m* of the box is withdrawn for using the tinder-box, but I wish it to be understood, that I do not limit myself to the particular form of automatically opening said valve, as the same might as well be opened by hand or by any suitable device.

As will be seen in the drawings, a small channel *b* is provided in the partition *h* between the fountain *a* and the wad-chamber *c*, the said channel *b* being placed at the lower end of said partition, to allow of a ready passage of the fuel when the slide-valve *i*, which covers and shuts said channel, is withdrawn. The said valve carries at its forward end a nose *n*, which is made to enter into an aperture or notch within the front wall of the wad-chamber *c* by means of a spring *k*, one end of which is attached to said wall, the other end being fixed to the slide-valve *i*. When the cover *m* of the box is put on the said snugly-fitting cover presses the said nose *n* of the slide-valve back into the chamber *c*, whereby the said spring *k* becomes stretched, as shown in Fig. 7. On removing the cover *m*, see Fig. 8, the said spring *k* will draw the nose *n* into the aperture of the wall and the valve-end *i* of the slide-valve will uncover the channel *b*, to let the fluid pass.

It will be readily understood, that the form of the slide-valve shown in the drawings, is not at all essential; any other valve, for instance a flap-valve, would do the same performance. Also the valve could be opened or shut by the agency of the hand.

A lamp of this kind may be safely carried in the pocket without any care whether one or the other of its ends be placed upper- or lowermost, as the passage of fuel through the channel *b* can only occur after opening the cover *m*. Besides the economy of fuel obtained, the lamp will also be kept clean of any escape of fuel.

A wick or porous material may be placed into the channel or before the same to obtain a slow passage of the fuel, if desired.

For using this construction as a lamp burning for a considerable space of time, it will be preferable to provide means for facilitating the passage of fuel from the fountain *a* to the wad-chamber; such means will best consist in establishing an entrance of air within the fountain *a*. A construction of this kind is shown, as an example, in Figs. 10, 11, and 12, corresponding to

Figs. 7, 8, and 9. It is similar to the construction of these latter figures and materially differs only in that, besides the channel *b* for the discharge of fuel, another channel *o*, is provided within the partition *h* in the opposite corner of the chamber *a*, to which channel *o* corresponds another channel *p*, within the slide of the valve *i*. In the state of repose, when the valve *i* keeps the channel *b* shut up, the other channel *o* will be equally shut up and closed by the slide of the valve, and when said slide is made to uncover the channel *b*, either automatically, as described before, or by hand, the channel *p* will be placed over the channel *o*, thus allowing air to enter into the fountain and help to expel the fuel into the wad-chamber.

In the drawings, both channels *b*, and *o*, are opened and closed simultaneously by one and the same slide containing the valve *i* and the channel *p*, but, of course, separate valves for both channels *b* and *o* might be provided and operated by separate means of any kind.

The second valve *p*, may be left away in case of the channel *o* being so lodged above the level of the fuel to exclude the passage of fuel through said channel or in case of the channel being protected through a sieve or perforated plate, such as *q* in Figs. 5 and 6. The said channel *o*, besides, may be provided in any other wall or side of the fountain *a*, the only requirement being that, to permit the entrance of air into said fountain.

As has been stated before, the shape and construction of the tinder-box may vary within wide degrees, if only two separate chambers are provided, one of them serving as a fountain for the fluid fuel and the other containing the wick destined to be lighted. Also the mode and means for lighting the flame may vary at pleasure, though, I prefer to construct the tinder-box as one to be lighted by pyrophorous means.

Instead of closing the tinder-box by a cover, such as *m*, Figs. 3, 4, 5, 6, 7, 8, 10, and 11, any other covering means, such for instance, as a hinged cap or a slide-plate, might be employed which may equally be constructed and arranged to automatically operate the covering and uncovering of the channels *b* and *p*.

I claim as my invention:

1. An improved tinder-box containing a fluid fuel, the same embodying a receptacle for the fuel, a burner, a wick, a chamber containing fibrous material and a reticulated medium in position to prevent the fluid from being thrown on the end of the wick of the burner if the latter is shaken.

2. An improved tinder-box containing a fluid fuel and comprising a reversible burner, fibrous material and a wick having one end

extending thereinto, said burner embodying a solid bottom and a reticulated bottom through which latter the wick extends.

3. An improved tinder-box containing a fluid fuel, comprising a reversible burner in which the fountain holds a wick passing through said fountain and through a perforated bottom of the same above the solid bottom.
- 10 4. An improved tinder-box containing a fluid fuel-fountain, comprising a fuel chamber, fibrous material for coöperation with the wick, and a wick-chamber juxtaposed to the fountain and a wick passing through the fuel chamber and into said fibrous material, said wick chamber communicating with said fountain through a channel so located that only in the state of use the fuel can pass through said channel.
- 20 5. An improved tinder-box containing a fluid fuel-fountain, comprising a fuel chamber, fibrous material for coöperation with the wick, and a wick-chamber juxtaposed to the fountain, a wick passing through the fuel chamber and into said fibrous material, a discharge-channel from the said fountain

into the wick-chamber, said channel being so located that only in the state of use the fuel can pass through said channel, and an entrance channel leading air into the fountain.

30 6. An improved tinder-box containing a fluid fuel-fountain, comprising a reversible burner having a wick-chamber juxtaposed to the fountain, a discharge-channel from the said fountain into the wick-chamber and means for automatically closing said channel on closing the tinder-box.

35 7. An improved tinder-box containing a fluid fuel-fountain, comprising a reversible burner having a wick-chamber juxtaposed to the fountain, a discharge-channel from the said fountain into the wick-chamber, a channel feeding air into the fountain and means for automatically closing both channels on closing the cover of the tinder-box.

40 In testimony whereof I affix my signature in the presence of two witnesses.

KARL WIEDEN.
